United States Patent Office

Des. 228,491
Patented Oct. 2, 1973

228,491

FOLDING DOOR

Forrest L. Dunsmoor, Oskaloosa, Iowa, assignor to
Rolscreen Company, Pella, Iowa

Filed Mar. 29, 1971, Ser. No. 128,900

Term of patent 14 years

Int. Cl. D25—02

U.S. Cl. D13—1 M

FIG. 1.

FIG. 5.

FIG. 7.

FIG. 6.

FIG. 1 is a perspective view of the folding door embodying my new design with the door being in a slightly folded position and with the dotted lines being disclosed for illustrative purposes only and forming no part of the claimed design;

FIG. 2 is an enlarged plan view of contiguous sections of a portion of the embodiment of FIG. 1;

FIG. 3 is a cross-sectional view taken along the line 3—3 of the embodiment of FIG. 2;

FIG. 4 is a cross-sectional view taken along the line 4—4 of the embodiment of FIG. 3;

FIG. 5 is a plan view similar to FIG. 2 showing an alternate design;

FIG. 6 is a sectional view taken along the line 6—6 of the embodiment of FIG. 5;

FIG. 7 is a cross-sectional view taken along the line 7—7 of the embodiment of FIG. 5;

FIG. 8 is an enlarged plan view similar to that of FIGS. 2 and 5, of a second alternate embodiment of my design;

FIG. 9 is a cross-sectional view taken along the line 9—9 of the embodiment of FIG. 8;

FIG. 10 is a cross-sectional view taken along the line 10—10 of the embodiment of FIG. 8.

FIG. 11 is an enlarged plan view, similar to that of FIGS. 2, 5, and 8, of a third alternate embodiment of my design;

FIG. 12 is a cross-sectional view taken along the line 12—12 of the embodiment of FIG. 11; and

FIG. 13 is a cross-sectional view taken along the line 13—13 of the embodiment of FIG. 11.

I claim:

The ornamental design for a folding door, as shown and described.
